(57) **CLAIM**

I claim the ornamental design for a set of portable sheet metal bending devices, as shown and described.

DESCRIPTION

FIG. 1 is a perspective view of a set of portable sheet metal bending devices showing my new design;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof; and,

FIG. 6 is a bottom plan view thereof.

1 Claim, 5 Drawing Sheets

FIG. 2.

FIG. 4.

FIG. 5.

FIG. 6.
